John M. Schellman
ATTORNEY.

UNITED STATES PATENT OFFICE.

CHARLES F. BOWLUS, OF DALLAS, TEXAS.

HEATER.

1,353,312.

Specification of Letters Patent.

Patented Sept. 21, 1920.

Application filed December 2, 1919. Serial No. 341,938.

To all whom it may concern:

Be it known that I, CHARLES F. BOWLUS, a citizen of the United States, residing at Dallas, in the county of Dallas and State 5 of Texas, have invented certain new and useful Improvements in Heaters, of which the following is a specification.

My invention relates to improvements in heaters and in such connection it relates 10 more particularly to a heater for bath tubs and such like and to the arrangement and construction of such a heater.

The principal object of my invention is to provide a device of this character which 15 may be placed directly underneath the bath tub and heat the water in the tub, and at the same time act as a heater for the bath room.

Another object is to provide a device of 20 this character which is simply constructed and arranged and which can be very cheaply manufactured.

My invention will be more fully understood from the following description, taken 25 in connection with the accompanying drawings, forming part hereof, in which—

Figure 1 is a side elevational view of a bath tub also a side view of the heater in position underneath the tub.

Fig. 2 is a top or plan view of the heater with part of the top broken away.

Fig. 3 is a cross sectional view of Fig. 2 taken on line 3—3 thereof, and

Figs. 4, 5 and 6 are detail views respectively of the air and gas inlet arrangement and means for supporting the interior panel.

Referring more particularly to the drawings, 1 represents a bath tub of any standard make with the usual inlet and outlet 40 pipes 2 and 3, underneath which tub is placed the heater. The heater is constructed of sheet metal and has its side walls 4—4 slanted obliquely inward and the top or upper part having the ridges 5 with openings 45 6—6 constituting the burners. The lower end of each side wall 4 is bent outward as shown in Fig. 3 to form a channel to receive the bottom plate 7 of the heater, both ends of which are closed by the end plates 8.

Inside the heater is arranged a panel 9 which is attached to one of the walls 4, its lower end supported upon an angular strip

10 riveted to the bottom plate 7. The panel 9 it will be noted by reference to Fig. 2 extends to within a short distance of the end 55 walls 8, leaving a space between the end walls and the ends of the panel 9, and there is also a space between the bottom of the panel 9 and the bottom of plate 7.

On one of the outer side walls 4 is arranged a triangular shaped box 11, the face 12 of which has the circular apertures 13—13 for admitting air for mixture with the gas and a circular opening 14 for the nipple of a cock 15 which will be referred 60 to later. Inside the box 11 and traversing the front wall 4 is a tube 16 for entrance of the gas. A plate 17 connected to the bottom plate 7 supports the gas cock 15.

The gas cock 15 is of the ordinary type 70 with the usual nipple 16^a on its forward or discharge end for spraying the gas. On the nipple 16^a is screw threaded a thimble 17^a with an opening 18 relatively larger than the openings in thimbles heretofore employed with the cock. This thimble when advanced or retracted on the nipple serves to decrease or increase the volume or density 75 of the spray of gas.

The mixture of gas and air passes through 80 the tubular opening 16 into the heater, thence under the panel 9 and between the end walls 8 and the ends of the panel into the larger compartment of the heater. It is thus thoroughly mixed with the oxygen 85 in the air and rises into the burner top 5, being ignited as it passes through the openings 6—6.

The heater can be very cheaply manufactured and will not crack the enamel on the 90 bath tub or smoke the surface of the tub.

Having thus described the nature and objects of my invention, what I claim as new and desire to secure by Letters Patent is—

1. A heater for bath tubs and the like 95 preferably oblong in shape and adapted to be placed underneath a bath tub and having its sides slanted obliquely inward and its ends vertical, the top of the heater forming a plurality of upwardly extending V-shaped 100 protuberances with perforations and constituting burners for the heater, a panel within the heater attached to the front wall of the heater with a space between each end

of the panel and the ends of the heater, said panel supported upon strips connected to the bottom of the heater and forming a space between the bottom of the panel and the bottom of the heater for the circulation of gas.

2. A heater for bath tubs preferably oblong in shape with inwardly slanted sides, vertical ends and V-shaped burners on its top, a panel within the heater, in combina-

tion with a gas cock having a conical spraying nipple and a thimble thereon a relatively large opening in the end of the thimble, whereby when the thimble is advanced or retracted on the nipple the density of the 15 gas is decreased or increased.

In testimony whereof I have signed my name to this specification.

CHARLES F. BOWLUS.
